UNITED STATES PATENT OFFICE

2,587,455

SECONDARY FEED AND MOISTENING DEVICE FOR HECTOGRAPH DUPLICATING MACHINES

Ronald Max Ford, Sparkbrook, Birmingham, England

Application July 8, 1950, Serial No. 172,664
In Great Britain October 10, 1949

10 Claims. (Cl. 101—132.5)

1

This invention relates to a duplicating machine of the kind having a frame in which is mounted a cylinder to which is secured a master sheet having the matter to be reproduced in reverse, the machine also comprising moistening means for the copy sheets, a feed tray for the copy sheets and a pressure roller to press the moistened copy sheets into contact with the master when the cylinder is revolved.

In such machines it is usual to attach the master to the cylinder by means of a clip on the cylinder, and it is necessary at starting that this clip shall occupy a definite position in relation to the line of contact between the cylinder and the pressure roller. For this reason it is usual to provide what are generally known as registration means to bring the cylinder to rest temporarily when the master sheet clip is in the correct position for feeding-in the copy sheet. Such registration means usually take the form of a spring-loaded lever having a roller which drops into engagement with a notch in the periphery of a flange rotating with the cylinder.

It is known in connection with such machines to provide for sheet reproduction, i. e. for reproducing the full width of the sheet on the master. It is also known to provide a master which when secured to the cylinder has its lines running circumferentially, and in connection with these machines it is known to provide the machine with a plurality of feed-in trays each of a width considerably less than the length of the cylinder and to provide for the adjustment of these feed-in trays parallel to the length of the cylinder so that portions of the matter on the master sheet can be reproduced.

A machine of this kind is disclosed in my prior U. S. A. application No. 103,933, filed July 9, 1949, this machine comprising a plurality of feed trays co-operating with a single cylinder, the trays being so disposed that the copy sheets guided by one tray or set of trays are delivered to the cylinder at one position, and copy sheets guided by the other tray or set of trays are delivered to the cylinder at a second position, which is angularly spaced from the first position, the two positions being circumferentially spaced around the cylinder, and one tray or set of trays being used for secondary reproduction, i. e. reproduction of a part only of the matter on the master sheet, and the other tray being used for reproduction of all the matter on the master sheet, means being provided whereby the angular position of the cylinder can be changed in relation to registration stop means, providing one

2

registration position when one tray or set of trays are in use, and another registration position for use when the other tray is in use.

In this machine the or each secondary tray is provided with a pressure roller acting on the cylinder, and means are provided for moving the or each secondary tray to bring its pressure roller out of contact with the cylinder at the registration position of the cylinder.

10 The machine also includes means for automatically moving one of the set of secondary trays laterally with a step-by-step movement so that successive sheets fed over the tray will receive matter occurring in adjacent lines on the master sheet.

15 The object of the present invention is to provide an improved and simplified construction and arrangement of parts, in this kind of machine, for the purpose of secondary reproduction, i. e. reproduction of a part only of the matter on the master sheet.

20 The invention is illustrated in the accompanying drawings, wherein:

25 Figure 1 is a view looking on one side of the machine;

Figure 2 is a section on the line 2—2 of Figure 6;

Figures 3 and 3a are plan views of the machine;

Figure 4 is a detail view in front elevation

30 showing a part of the machine;

Figure 5 is a fragmentary plan view showing the tooth on the lever which co-operates with the racks; and

Figure 6 is a section on the line 6—6 of Figure 3.

35 In the construction illustrated the side frame members 10, cylinder 11, cylinder shaft 12, and the tray and pressure roller for sheet reproduction, are in accordance with the prior specification referred to. The means, indicated generally at 13, for adjusting the cylinder around its axis in relation to the registration stop means are also constructed and arranged in accordance with the prior invention.

40 Further, two secondary trays 14 and 15 are provided both of which are adjustable laterally, and the tray 14 may be adjusted automatically with a step-by-step motion, the means for effecting this incorporating a fixed rack 16 and a reciprocating rack 17 operating in the same manner as the corresponding parts disclosed in the prior specification.

45 In the present construction the supports 20 of the secondary trays are each provided with a bracket 18 which is mounted on a bar 19 con-

necting the side member 10 of the frame, and each of these supports is provided with a bracket 21 at the rearward end carrying a pressure roller 22 which can be moved into contact with the master sheet on the cylinder. In the present construction the tray supports are rocked around the axis of the bar 19 to effect this movement which is produced by an oscillating shaft 23 having a flat 24 which engages the underside of a lever 25 pivoted at 26 to a bracket 27 on the underside of the tray support. A compression spring 28 is provided acting between each lever 25 and the underside of the tray support.

Further, each of the supports for an auxiliary tray is provided with a damping member 29 pivoted at 30 and operated by a cam 31, as described in the prior specification referred to. The cam 31 is adapted to be rocked about its pivot 32 by a lever 33 which carries a roller 34 co-operating with a registration notch 35 in the periphery of a disc 36 fixed to the cylinder shaft.

The lever 33 is pivoted at 37 on the outer side of one of the plates 10, and it is acted upon by a spring 38 which engages an abutment 39 on the frame member. As the notch 35 passes the roller 34 the lever is rocked, and this motion causes the spindle 40 of the damping roller used for sheet reproduction to be moved, and also causes the cam 31 to be rocked. The cam is provided with a lever 41 having a projecting pin 42 which engages in a slot in the lever 33.

Further, the shaft 23 is rocked by a lever 44 on the outer side of the frame member 10, this lever having a pin 45 engaging in a slot 46 in the lever 33.

Each time the shaft 23 is rocked it moves the tray support pivotally and brings the pressure roller 22 into contact with the master.

At one or more positions, for instance at its ends, and again at the centre if desired, the shaft 23 may be provided with portions 47 of reduced diameter and without flats so that when the secondary trays are one at each end of the machine or at a selected intermediate position they are not rocked.

The means for imparting automatic step-by-step movement to the tray 14 are similar to those described in the prior specification and incorporate the reciprocating rack 17 and the stationary rack 16. The support of the secondary tray 14 is provided with a downwardly-projecting bracket 48 to which is pivoted at 49 a lever 50 having an adjustable screw 51 which can be engaged by a bar 52 carried by cranks 53 on the shaft 23 so that when the shaft 23 is rocked the lever 50 is rocked to bring a tooth 54 out of the rack 17 and into the rack 16. When the reverse movement takes place the tooth 54 again engages the reciprocating rack 17, to which a constant tension is applied by a cable 55, as described in the prior specification, and the tray support of the tray 14 is moved one step towards the left-hand end of the machine, as shown in Figure 3.

The tooth 54 is pivoted at 95 to the lever 50, and the tooth is of ratchet form and is acted upon by a tension spring 96 so that the tray 14 can always be moved by hand to the right, as shown in Figure 3, but at certain times is locked against movement to the left.

The lever 50 is provided with a finger piece 56 so that it can be moved downwardly by hand to bring the tooth 54 clear of both racks 16 and 17 to permit the tray to be moved laterally and freely.

The lever 50 is provided with an adjustable screw 57 which forms a stop.

The two side plates may be connected by a member, indicated at 58, upon which a row of figures are marked corresponding with the lines of the master, and the tray support 20 may be provided with a mask 59 provided with an opening 60 so that the operator can see which line will be reproduced on a card or sheet passed over the tray 14 which is mounted on the tray support 20.

The tray 14 may be provided with a slide 61 engaging in a guide 62 fixed to the underside of the tray support 20 and providing sufficient friction to retain the tray in any position into which it is moved.

The tray 14 may be of channel section, as shown, and at its rearward end it may be provided with a shield 63 under which the cards are passed.

The other secondary tray 15 is mounted on a tray support 64 (see Figure 4), and this tray support, which is mounted on the bar 19, is movable along the bar and is provided with a lever 65 a portion of which can be engaged in one of two notches 66 in a bar 67 connecting the end frames of the machine. The lever 65 is pivotally mounted at 68 to a block 69 on the tray support 64.

The tray 15, which is shaped similarly to the tray 14, is mounted on the top of the tray support, and it is spring-loaded by a spring 70 having one end connected to a pin 71 on the tray and the other end connected to a pin 72 on the tray support. A spring-loaded lever 73 is provided on the tray adapted to engage with any of the notches 74 in a rack 75 on the tray support.

In this machine each of the trays 14 and 15 is provided with its own moistening means incorporating a container 76 for the moistening liquid and a pipe 77 through which extend a plurality of wicks 78. Each tray support is provided with a U-shape bracket 79 upon which is mounted a plate 80 carrying an absorbent pad 81 a portion 82 of which extends downwardly through a slot and can be adjusted by a nut 83 on a pin 84.

Each of the members 79 is provided with lugs 85 to which is pivoted a lever 86 carrying a pressure plate 87; also fitted with a moistening member 88. Each of the members 86 is spring-loaded by a spring 89 tending to move the two absorbent members 88 and 81 into contact.

Liquid is fed to both absorbent members, one strand of the wick being taken to the lower absorbent member 81 and a plurality of strands of the wick being taken to the other absorbent member 88.

The machine is provided with a bar 90 connecting the two members 10, and adjustably mounted on this bar are a plurality of brackets 91 each carrying a pin 92 which forms an adjustable abutment adapted to engage with inclined surfaces 93 at the corners of the levers 86, the arrangement being such that when the trays 14 and 15 are moved along the machine into certain positions, the pressure plates 80 of the moisteners are raised so as to bring the two absorbent members out of contact. This will occur when the machine is out of use and the two trays 14 and 15 are moved to the ends of the machine.

The two side members are of course connected

at intervals by bars, one of which can be seen at 61.

The reciprocating rack 17 is spring-loaded towards the right, as shown in Figure 3 and as described in the prior specification referred to.

A pivoted movable stop 96 is provided on the frame operating between two stop pins 97 and capable of being rotated in an anticlockwise direction, as seen in Figure 4, to lock the rack 17 against endwise movement should it be desired to keep the tray 14 in one position for an indefinite period for taking a number of copies of the same matter from the master.

What I claim then is:

1. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, a bracket pivotally mounted upon said bar, a support for a tray mounted on said bracket, a pressure roller carried by said support, and disposed between the master cylinder and the tray so as to engage the master cylinder when the tray is moved towards the cylinder, a shaft mounted for oscillation within the frame and having means for engaging the tray support to cause pivotal movement thereof about the axis of said bar when the shaft is oscillated, a lever pivotally mounted on one side frame member, and means on said lever adapted to co-operate with the cam of the registration means on the master cylinder, said lever being adapted to oscillate said shaft.

2. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, a pair of spaced brackets pivotally mounted upon said bar, a support for a tray mounted on said brackets, a pressure roller carried by said support, and disposed between the master cylinder and the tray so as to engage the master cylinder when the tray is moved towards the cylinder, a further bracket fixed on the underside of said support, a lever pivoted on said further bracket, a shaft mounted for oscillation within the frame, a flat on said shaft adapted to engage the lever pivoted on the further bracket fixed on the support to cause pivotal movement thereof about the axis of said bar when the shaft is oscillated, a lever pivotally mounted on one side frame member, and means on said last-mentioned lever adapted to co-operate with the cam of the registration means on the master cylinder, said last-mentioned lever being adapted to oscillate said shaft.

3. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, a pair of spaced brackets pivotally mounted upon said bar, a support for a tray mounted on said brackets, a pressure roller carried by said support, and disposed between the master cylinder and the tray so as to engage the master cylinder when the tray is moved to-

wards the cylinder, a further bracket fixed on the underside of said support, a lever pivoted on said further bracket, a shaft mounted for oscillation within the frame, said shaft having portions of circular form and portions with flats adapted to engage the lever pivoted on the further bracket fixed on the support, to cause pivotal movement thereof about the axis of said bar when the shaft is oscillated, a lever pivotally mounted on one side frame member, and means on said last-mentioned lever adapted to co-operate with the cam of the registration means on the master cylinder, said last-mentioned lever being adapted to oscillate said shaft.

4. In a duplicating machine of the kind described having a master cylinder and registration means comprising a cam rotatable with the master cylinder and at least one feed-in tray for delivering copy sheets to the master cylinder, a frame including a pair of spaced parallel side frame members, a bar mounted between said side frame members, a pair of spaced brackets pivotally mounted upon said bar, a support for a tray mounted on said brackets, a pressure roller carried by said support, and disposed between the master cylinder and the tray so as to engage the master cylinder when the tray is moved towards the cylinder, a further bracket fixed on said support, a lever pivotally mounted thereon, a rack mounted within the frame, a tooth pivoted on said lever adapted to engage said rack, a shaft mounted for oscillation within the frame and having means for engaging the secondary tray support to cause pivotal movement thereof about the axis of said bar when the shaft is oscillated, a crank arm at each end of said shaft, a bar connected between said arms and adapted to engage the said lever, a lever pivotally mounted on one side frame member and means on said last-mentioned lever adapted to co-operate with the cam of the registration means on the master cylinder, said last-mentioned lever being adapted to oscillate said shaft.

5. In a duplicating machine of the kind described having a master cylinder and registration means comprising a cam rotatable with the master cylinder and at least one feed-in tray for delivering copy sheets to the master cylinder, a frame including a pair of spaced parallel side frame members, a bar mounted between said side frame members, a pair of spaced brackets pivotally mounted upon said bar, a support for a tray mounted on said brackets, a pressure roller carried by said support, and disposed between the master cylinder and the tray so as to engage the master cylinder when the tray is moved towards the cylinder, a first bracket fixed on the underside of said support, a first lever pivoted on said first bracket, a second bracket fixed on said support, a second lever pivotally mounted on said second bracket, a rack mounted within the frame a tooth pivoted on said second lever adapted to engage said rack, a shaft, a flat on said shaft adapted to engage said first lever on the support to cause pivotal movement thereof about the axis of said bar when the shaft is oscillated, a crank arm at each end of said shaft, a bar connected between said arms and adapted to engage the said second lever, a lever pivotally mounted on one side frame member, and means on said last-mentioned lever adapted to co-operate with the cam of the registration means on the master cylinder, said last-mentioned lever being adapted to oscillate said shaft.

6. In a duplicating machine of the kind de-

scribed having a master cylinder and registration means comprising a cam rotatable with the master cylinder and at least one feed-in tray for delivering copy sheets to the master cylinder; a frame including a pair of spaced parallel side frame members, a bar mounted between said side frame members, a pair of spaced brackets pivotally mounted upon said bar, a support for a tray mounted on said bracket, a pressure roller carried by said support, and disposed between the master cylinder and the tray so as to engage the master cylinder when the tray is moved towards the cylinder, a secondary tray movably mounted on said support, a shield on said tray below which copy sheets can pass, a shaft mounted for oscillation within the frame and having means for engaging the secondary tray support to cause pivotal movement thereof about the axis of said bar when the shaft is oscillated, a lever pivotally mounted on one side frame member, and means on said lever adapted to co-operate with the cam of the registration means on the master cylinder, said lever being adapted to oscillate said shaft.

7. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, two pairs of spaced brackets pivotally mounted upon said bar, a support for a tray mounted on each pair of brackets, a tray mounted on each support, spring means acting on one tray for moving said tray transversely of the frame, means for retaining said tray in any one of a number of positions, a pressure roller carried by each support, and disposed between the master cylinder and the tray so as to engage the master cylinder when the tray is moved towards the cylinder, a shaft mounted for oscillation within the frame and having means for engaging each secondary tray support to cause pivotal movement thereof about the axis of said bar when the shaft is oscillated, a lever pivotally mounted on one side frame member, and means on said lever adapted to co-operate with the cam of the registration means on the master cylinder, said lever being adapted to oscillate said shaft.

8. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, a pair of spaced brackets pivotally mounted upon said bar, a support for a tray mounted on said brackets, a pressure roller carried by said support, and disposed between the master cylinder and the tray so as to engage the master cylinder when the tray is moved towards the cylinder, moistening means on said support including a liquid container, a wick and a moistening pad for moistening copy sheets, a shaft mounted for oscillation within the frame and having means for engaging the tray support to cause pivotal movement thereof about the axis of said bar when the shaft is oscillated, a lever pivotally mounted on one side frame member, and means on said lever adapted to co-operate with

the cam of the registration means on the master cylinder, said lever being adapted to oscillate said shaft.

9. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members, a pair of spaced brackets, pivotally mounted upon said bar, a support for a tray mounted on said brackets, a pressure roller carried by said support; and disposed between the master cylinder and the tray so as to engage the master cylinder when the tray is moved towards the cylinder, moistening means on said support comprising a liquid container, two absorbent pads, one pad being fixed in relation to the support, a spring loaded pressure plate pivotally mounted on the support having the other pad carried thereon, wicks for feeding liquid to each pad, and an abutment on the machine frame for automatically moving the pad on the pressure plate away from the other pad at one position of the tray support; a shaft mounted for oscillation within the frame and having means for engaging the tray support to cause pivotal movement thereof about the axis of said bar when the shaft is oscillated, a lever pivotally mounted on one side frame member, and means on said lever adapted to co-operate with the cam of the registration means on the master cylinder, said lever being adapted to oscillate said shaft.

10. In a duplicating machine of the kind described having a master cylinder and registration means comprising a cam rotatable with the master cylinder and at least one feed-in tray for delivering copy sheets to the master cylinder; a frame including a pair of spaced parallel side frame members, a bar mounted between said side frame members a bracket pivotally mounted upon said bar, a support for a tray mounted on said bracket, a pressure roller carried by said support, and disposed between the master cylinder and the tray so as to engage the master cylinder when the tray is moved towards the cylinder, a shaft mounted for oscillation within the frame and having means for engaging the tray support to cause pivotal movement thereof about the axis of said bar when the shaft is oscillated, a lever pivotally mounted on one side frame member, and means on said lever adapted to co-operate with the cam of the registration means on the master cylinder, said lever being adapted to oscillate said shaft.

60 RONALD MAX FORD.
